CONCEALABLE IRONING BOARD

Filed June 3, 1926

UNITED STATES PATENT OFFICE.

PAUL E. JOSEPH, OF OAKLAND, CALIFORNIA, ASSIGNOR TO CHICAGO LUMBER COMPANY OF WASHINGTON, OF OAKLAND, CALIFORNIA, A CORPORATION OF DELAWARE.

CONCEALABLE IRONING BOARD.

Application filed June 3, 1926. Serial No. 113,391.

My invention relates to a built-in ironing board of the concealable type and particularly to a mounting for the board which permits the operative positioning of the 5 board in different horizontal planes.

An object of the invention is to provide a device of the class described which affords a particularly rigid support for the board when operatively extended in its adjusted 10 positions.

Another object of the invention is to provide a structure which provides a sleeve board arranged to be operatively supported upon the ironing board in the different adjusted 15 positions of the latter.

A further object of the invention is to provide a structure which may be installed as a unit entirely within a wall of ordinary structure and thickness.

20 The invention possesses other objects and features of advantage, some of which, with the foregoing, will be set forth in the following description of the preferred form of my invention which is illustrated in the 25 drawings accompanying and forming part of the specification. It is to be understood that I do not limit myself to the showing made by the said drawings and description, as I may adopt variations of the preferred 30 form within the scope of my invention as set forth in the claims.

Referring to said drawings,

Figure 1 is a side elevation of the structure of my invention showing the various 35 parts thereof extended in operative position.

Figure 2 is a perspective view showing the device disposed in a wall cavity with the various parts in inoperative, or folded, position.

40 Figure 3 is an enlarged view of a portion of the showing of Figure 1.

As illustrated in the drawings, the device of my invention comprises an ironing board 3 mounted in a cabinet 4 arranged to fit 45 between studding 5 of a wall 6 of usual

structure, the cabinet preferably being of such dimensions that a special wall structure will not be required to permit its mounting therein. As shown, the cabinet 50 is rectangular and is formed with side walls 7, top and bottom walls 8 and 9 respectively, and a back wall 11. The front edge of the cabinet is preferably provided with a casing 12 here shown overlying the forward

edges of the top and side walls and extending 55 to the floor 13, closure for the opening defined by the casing being provided by means of a sectional door 14 hingedly secured to the casing at one side of the opening.

Structural provision for mounting the cabinet in the wall consists merely in the provision of a header member 15 extending at the proper height between the studding 5, and in terminating the front wall finish 16 60 at the edges of the space thus defined between the studding, the header 15, and the floor plate 15'. It will now be noted that with the over-all depth of the cabinet from the plane of the back of the casing no greater 65 than the studding depth plus the thickness of the wall surface 16, and the cabinet narrow enough to fit between the studding, the latter may be constructed and assembled at some other point and then mounted as a unit 70 in the space provided therefor. Since a special wall thickness or structure is not required, it will be obvious that the device is equally adapted for installation in old and new houses, it being noted that it may 75 readily be dimensioned for installation in walls formed with studding as narrow as substantially three inches.

The ironing board 3, it will now be noted, is arranged to be supported by, and entirely 80 from within, the cabinet. As here shown, the cabinet side walls 7 are provided with vertical slots 17 appropriately positioned and having sets of sockets 18 and 19 respectively communicating therewith and extending 85 forwardly therefrom, the sockets of a set being in opposed relation, with the sockets 18 above the sockets 19. Fixed at an end 21 of the board are pivots 22 slidably engaged in said slots and arranged to be seated 90 in said sockets so that the board is thus thereby pivotally secured to the cabinet and may extend from the level of either set of 95 sockets.

Means are provided for supporting the 100 board in horizontally extended position, and as here shown, such means comprise the provision of a pair of struts 23 pivotally secured to the board and cabinet. The struts 23, it will be noted, are here shown pivotally 105 secured to the board by means of hinges 24, while at their other end they are pivotally connected to an edge 25 of a horizontally

disposed member 26 by means of hinges 27. The member 26, it will be noted, is mounted in and between the cabinet walls 7 for pivotal movement about a different horizontal axis than that of the hinges 27. Mounting of the member 26 is here shown most simply provided by means of pivot pins 28 extending therefrom to engage in suitable bearings provided in the side walls 7. It will now be noted that the struts are preferably attached adjacent the opposite ends of the member 26, while their spacing at the board is appreciably less than the spacing thus provided at the member 26, so that they co-operate to define a trapezoid in their plane to thereby provide a rigid brace against lateral displacement of the board as well as a support therefor.

As here shown, the member 26 is so shaped and mounted that when swung upwardly and back from the position shown in full lines in Figure 1, the edge 25 will bear against the back wall 11, as shown in dotted lines in the same figure, while its downward rotation from the first position is prevented by reason of its engagement with stops 29 here shown mounted on the outer edge of a transversely disposed member 29' fixed in the cabinet in appropriate position below the pivotal axis of the member 26. In this manner, it will be noted, pivotal movement of the member 26 is limited, and a substantially direct bearing for the struts is provided in either extreme position of the member 26. Since the back wall 11 may be formed of comparatively thin wood, the stops 29 may be also utilized to assist in limiting the backward movement of the member 26. As here shown, such is effected by so shaping and positioning the member 26 and stops 29 that an edge 30 of the former will bear against the rearward sides of the latter when the member 26 engages the wall 11. It will now be noted that the various parts are so related that when the board is extended horizontally outwardly from the upper sockets 18, the member 26 is arranged to be in bearing position against the stops 28, while with the board extended horizontally outwardly of the lower sockets 19, the member 26 is arranged to bear against the back wall 11 and stops 29, it being obvious that either of the latter might be used alone if so desired.

In this manner, positioning of the board in either horizontal plane is provided for, yet the pivotal association of the parts is maintained at all times and no adjustment of connections is required in changing the board from one level to another. It will now be particularly noted that the hinged connection of the struts and member 26, and the pivotal mounting of the latter together really provide a triple hinge structure with the member 26 forming the middle leaf,

the movement of the latter being, as here shown, limited to a fixed angular range of less than 180°.

When the board is swung upwardly into the cabinet, as shown in Figure 2, the pivots 70 move downwardly in the slots 17 and the member 26 assumes an intermediate position with all parts lying behind the plane of the casing to permit closing of the cabinet door.

A sleeve board 31 is also desirably provided. As here shown, the board 31 is pivotally secured to and between the side walls 7 at a point above and rearwardly of the sockets 18 so that it may be swung upwardly to lie between the back wall 11 and the board 3. Means are provided for holding the sleeve-board 31 in horizontally extended position, and as here shown, such means comprise a brace 32 mounted on the latter and arranged to engage the board 3 in either of its operative positions to properly position and support the board 31. As here shown, the brace 32 is arranged, when the board 31 is in its upper extended position, to engage a suitable stop provided adjacent the end 21 of the board 3, the member providing the pivots 22 being here shown utilized as a stop for the purpose. When the board 31 is in its lower operative position, the brace 32 is swung outwardly to a perpendicular position to bear at its other end on the board 3, as shown in dotted lines in Figure 2. In this manner, support for the sleeve board is provided at all times, and it may be disposed in the cabinet when not in use.

If an electric iron is to be used with the boards, means associated with the cabinet are provided for supporting the electric iron cord 36 so that it will depend from above the operator's head. As here shown, such means comprise the provision of a bracket arm 37 pivotally fixed at one end at the upper end of a cabinet side 7 and arranged to be disposed either vertically within the cabinet or horizontally outwardly therefrom, a stop 38 being provided for releasably securing the arm 37 in the last-mentioned position, it being noted that the cord 36 may be secured to or merely passed over the outer end of the arm 37 to be supported thereby.

As here shown, the cabinet is also arranged to serve as a broom closet by suitably notching the members 26 and 29' to receive the lower portion of the broom 41 and providing a suitable handle gripping device 42 on the under surface of the board 3.

It will now be particularly noted that a combined mounting and housing for a concealable adjustable ironing board have been provided which may be installed as a unit in a wall of ordinary thickness, and which at the same time provides a particularly rigid support for the ironing board.

While I have herein specifically described

a structure permitting the operative positioning of the ironing board at but two levels, it will be obvious that by use of additional sets of sockets for the reception of 5 pivots 22 and adjustably positionable stops for cooperation with the member 26, a range of more than two positions might be provided for without departing from the spirit of my invention.

30 I claim:

1. In a device of the character described, a cabinet, an ironing board, cooperating means on said cabinet and board engageable to secure the inner end of said board in either 15 one of a pair of adjusted positions in said cabinet, a strut member pivotally secured to said board, a member disposed across said cabinet and pivoted thereto at its ends, a hinge pivotally securing said strut member 20 to said second member, the pivotal axes of said second member and hinge being spaced and parallelly disposed, and a pair of fixed stops in said cabinet, different of said stops being operably engageable by said second 25 member in the different adjusted positions of said board end when said board is operatively disposed.

2. In a device of the character described, a cabinet, an ironing board, cooperating 30 means on said cabinet and board engageable to secure the inner end of said board in a pair of adjusted positions in said cabinet, a strut member having an end thereof pivotally secured to said board at an intermedi-

ate point thereof, a member disposed across 35 said cabinet and pivoted thereto at its ends, means pivotally securing said strut member at the other end thereof to said second member for rotation about an axis spaced from and parallel to the axis of said member, and 40 stop members provided in said cabinet and arranged to be engaged by portions of said second member adjacent the point of attachment of said strut thereto when said board is operatively disposed in each of its adjusted 45 positions.

3. Means for supporting an ironing board in operative position and at different levels, comprising a fixed support, cooperating means on said board and support engageable 50 to secure the inner end of said board to said support at said different levels, a strut member having an end thereof pivotally secured to said board at a point thereof outward of said inner board end, a member hinged to 55 said support for rotation about a fixed horizontal axis, means hingedly securing the other end of said strut to said last member about an axis spaced from and parallel to the fixed axis thereof, and stop members on 60 said support arranged to be operably engaged by said second member when said board is operatively disposed in each of its adjusted positions.

In testimony whereof I have hereunto set 65 my hand at Oakland, California, this 22nd day of May, 1926.

PAUL E. JOSEPH.
